[57] CLAIM

The ornamental design for a paper folding apparatus, as
shown and described.

DESCRIPTION

FIG. 1 is a right front perspective view of a paper folding
apparatus, showing my new design;
FIG. 2 is a side elevational view thereof;
FIG. 3 is a front elevational view thereof;
FIG. 4 is a rear elevational view thereof;
FIG. 5 is a top plan view thereof; and
FIG. 6 is a bottom plan view thereof.
